JOINT STRUCTURE

Albert E. Wagstaff, Frankfort, N. Y., assignor to
 International Heater Company, Utica, N. Y., a
 corporation of New York

Application June 8, 1942, Serial No. 446,314

1 Claim. (Cl. 189—36)

My present invention relates to a joint structure of general use and broad application but for definiteness it is illustrated and described as used for attaching the casing to the front of a warm air heater.

The purpose of my present invention is to provide new, improved and more convenient and efficient joint structure especially useful for attaching the casing, usually of thin sheet metal, to the side flanges of the front of a warm air heater.

A further purpose is to provide a joint structure which when used with the casing of a warm air heater has no exterior brackets or other parts required upon the casing and even no screws or bolts required upon the outside of the heater front.

Or stated in positive terms the purpose of my invention is to provide a joint structure which when applied to a warm air heater provides a construction wherein the vertical or end edges of the casing are provided or formed with a hook, as by turning inwardly and backwardly against the main portion of the casing a narrow strip of the casing, and to provide upon the side flanges of the front a series of inwardly extending rigid lugs spaced back from the edges of the flange, which lugs are adapted to have attached thereto a screw-threaded member, and then to provide adjustable and readily attachable and detachable clamps each comprising a hooked member adapted to engage a hook of the casing, and a screw-threaded member or device adapted to engage said flange lugs so that proper adjustment of said screw-threaded clamps will draw the ends of the casing circumferentially to and along the inner face of the side flanges and effect a permanent and air-tight joint.

A still further purpose of this invention is to provide a joint structure which when applied to a warm air heater has not only the necessary considerable range of adjustment circumferentially but also provides a fastening means that is adjustable over an indefinite range vertically so that if there should be slight inequalities in the ultimate mounting of the parts of the heater and of its front, the fastening means can still be attached and adjusted satisfactorily.

It will be seen that a joint structure having the above-mentioned characteristics will eliminate practically all of the numerous troublesome difficulties encountered in the installation and erection of the casings of warm air heaters. Most of the parts of my device are so small they would not show on a complete horizontal sectional view of a complete heater but Fig. 1 is a horizontal

sectional view on a small scale through a lower portion of a warm air heater to which is to be applied my joint structure for attaching the front ends of the casing to the side flanges of the front of the heater.

Fig. 2 is a horizontal sectional view similar to Fig. 1 but on an enlarged scale of the side flanges of the front of the warm air heater showing two sets of my fastening devices and the adjacent forward ends of the casing, the parts being shown in their ultimate or assembled position.

Fig. 3 is a sectional view similar to Fig. 2 but showing only one set of my fastening mechanism, the parts being shown in their position before the hooked clip of the clamp is connected to the adjacent hooked edge of the casing.

Fig. 4 is a view similar to Fig. 3 and showing only one set of the fastening mechanism but with the clip connected to the hooked edge of the casing, and before the casing is drawn up closely to the adjacent front flange.

Fig. 5 is a vertical sectional view on line 5—5 of Fig. 4.

Fig. 6 is an edge view of the angular-shaped clip and Fig. 7 is a side view thereof looking towards the left side of Fig. 6.

Fig. 8 is a perspective view of the clip portion of the clamp.

Referring to the drawing in a more detailed description it will be seen that my invention is applied to any conventional form of warm air heater having various parts of its body 11 fastened together in the usual manner and having its various operating passages 12 connected and secured to the vertically arranged front 13 of the heater, which front has its side edges provided with vertically arranged flanges 14 which are spaced out the proper distance from the body of the heater so as to be in the circle of the casing 15.

The forward edges or front ends of the casing are to be secured to said side flanges 14 by substantially air-tight joints so as to properly confine the air in the chamber formed between the various parts of the body of the heater and the casing which surrounds the heater except at the front of the heater where the said chamber is completed by the front 13 and the several operating passages 12. Thus far the parts mentioned are conventional and well known.

Upon the inner surface or face of each side flange 14 of the heater front 13 and spaced back from the adjacent outer edge of the flange 14 I provide several inwardly extending strong rigid lugs 16, most conveniently formed as an integral

part with the casting forming the front 13 and the side flanges 14. Towards its inner end each lug 16 is provided with a horizontally arranged transversely extending opening or aperture for the mounting on said lug of the shank 17 of a bolt 18. Such bolt-receiving aperture is commonly and preferably in the form of a hole 19 somewhat larger than the diameter of the shank 17 of the bolt 18.

Each forward edge of the casing 15 is provided with an inwardly arranged close hook 19 conveniently and preferably formed by turning inwardly and back against the adjacent main part of the said casing a relatively narrow edge strip of said casing. This hook it will be seen extends for the full width or height of the vertical front edges of each casing for a purpose that will hereinafter appear.

The clamp of my fastening device which is to draw and hold the hooked edge of the casing towards and to the inner face of the flange of the front with a substantially air-tight joint consists of the bolt 18 already mentioned, commonly having a rounded head 20 provided with a slot 21 for the convenient application to said bolt of an ordinary screw driver, a nut 22 fitting the screw-threaded shank 17 of said bolt 18 and a clip 23. This clip is conveniently formed from a piece or strip of proper weight and strength of metal bent or otherwise formed into angular shape with one arm as 24 having an aperture or opening 25 for the passage therethrough of the shank 17 of said bolt. The other arm is formed as a close hook 26 conveniently made by bending the outer half 27 of said arm forwardly and closely back towards the first part 28 of the arm.

It will be understood that the hook on the end of the casing is adapted to engage the hooked arm of the clamp and in general that these two hooked parts and the clamp as a whole and the lug 16 are so shaped and proportioned that the hook 19 of the casing may be caught into the hook 26 of the clamp on the inside of the flange and then by drawing up the bolt 18 against its arm 24 of the clip, the adjacent end of the casing 15 will be drawn up through the intermediate position of Fig. 4 to the final or assembled position of the parts shown in Fig. 2.

Ordinarily the casing 15 of such a warm air heater consists of two substantially equal upper and lower halves so that the assembler of the heater and its casing can conveniently reach over the top of the lower half to put the usual two clamps at each end of the lower half of the casing into preliminary engaged position. Ordinarily the clamps at one end of the casing will be attached first and then the clamps at the other end will be maneuvered into position, and then first one side or end of the casing will be drawn up circumferentially a short distance and then the other end of the casing will be in a similar manner drawn up, and these steps will be continued until this lower half of the casing is in final assembled position with the outer surface of the casing adjacent its hook closely pressed against the inner surface or face of the flange 14 outside the lugs 16. The material of which the clip of the clamp is composed is somewhat resilient but very strong so that the necessary pressure in setting up the bolt or its nut can be exerted through the clamp against the hooked end of the casing.

I have shown the head of the bolt as being mounted next to the apertured arm 24 of the

clip, as that is ordinarily the procedure in that it allows the workman to more conveniently apply a screw-driver to the head of the bolt, to rotate said bolt while the nut is held from rotation either by a wrench or other proper tool applied to said nut or by the friction of said nut upon its side of the lug. Obviously if it is more convenient the shank of the bolt can be inserted through the lug from the inner or right-hand side of the lug, as these lugs are seen in Figs. 3 and 4, and the nut then placed on the outer end of the bolt after said outer end has been slipped through the apertured arm 24 of the clip, whereupon the bolt and nut are tightened up in any desired manner as may be most convenient under the circumstances.

After the lower half or a bottom section of the casing has thus been caught into position and adjusted to its ultimate neat, tight and final position, the other, or another section will be assembled in position by the maneuvers already outlined, the workman or his helper reaching over the top of this section of the casing to get to the lower clamp, using for that purpose a box or stepladder if more convenient, and then easily getting access to the upper clamp. Ordinarily two of these clamps on each end of a section will be sufficient although according to the size of the heater front and somewhat according to the character of the casing, three or more clamps may be used spaced suitably along each end of a section. Ordinarily the lugs 16 will be positioned so as to bring a clamp a few inches from the upper or lower edge of a section of the casing and if more clamps are necessary they will be spaced at intervals along the edge. Of course when more clamps are to be used the necessary lugs will be provided along the flange of the front.

By having the main body of a section of the casing held in approximate position the hooked edge thereof may be readily brought into preliminary hooked engagement with the hook of the clamp. It will be noticed however that where it is more convenient the clip 23 of a clamp can be entirely disconnected from its lug 16 and then the hooked end of the clamp can be readily caught into the hook of the casing and then the clip brought up towards its lug; then by inserting the shank of the bolt through the clip and the lug the nut can be readily started into position, and after all the clamps are in at least preliminary engaging position rotation of the bolts or of the nuts will exert the necessary pressure to draw the ends of the casing circumferentially into neat and air-tight position as required.

It will be noted particularly that as the casing hook 19 extends for the full vertical width of the casing edge the clips can always readily be placed in position to cooperate with their appropriate lugs. This is a decided improvement over constructions heretofore used where a part of the cooperating fastening means was located upon the casing before the casing was mounted about the heater, since such preliminary mounting of a part of the fastening mechanism often failed to have its parts properly aligned for convenient and neat attachment.

It will now be seen that the fastening herein illustrated and described is entirely complete without the use of any exterior brackets or bolts or other parts upon the casing or upon the front of the heater. It will be seen also that my system of fastening means permits ready dismounting of the casing from the heater whenever that is required, as for making repairs upon the heater

or replacing parts thereof. In such dismounting no part of the clamp or of the casing is damaged and the parts can be readily reassembled following the procedure outlined for the first installation.

What I claim is:

A means for adjusting and fastening a flexible sheet metal casing to the opposite edges of a rigid front panel of a furnace wherein the panel has short inwardly projecting posts spaced back from each edge of the panel and each post is provided with a transverse bolt-receiving aperture near its free end and the spaced ends of the casing are turned inwardly and back and making a close hook extending the full width of the casing at each end thereof, said adjusting and fastening means consisting of a series of three part clamps, each comprising a bolt and a cooperating nut and an L-shaped-clip, the shank of

which clip has a bolt-receiving aperture near its free end and the base portion of which L is a close hook each of said hooks of the clips being slidably mounted in an adjacent casing hook for free adjustability along the width of the casing whereby on the parts being assembled with said clamp hooks engaging the oppositely disposed parts of said hooked ends of the casing and with said clip shanks respectively opposite a post and connected thereto by a bolt and nut, relative rotation of the bolts and nuts in the proper direction will draw the hooked edge of each end of the casing towards its adjacent posts and will press the outer surface of said hooked ends of the casing against the inner surface of the panel and the casing may be adjusted relative to the front panel of the furnace.

ALBERT E. WAGSTAFF.
